WEARING PART FOR CRUSHERS

Oscar C. Gruender, Milwaukee, Wis., assignor to
Nordberg Manufacturing Company, Milwaukee, Wis., a corporation of Wisconsin

Application November 30, 1938, Serial No. 243,094

2 Claims. (Cl. 83—10)

My invention relates to an improvement in 5
wearing parts for crushers and has particular applicability to a bowl liner for crushers in which a crushing head is gyrated or otherwise moved within a concave bowl.

One purpose is the provision of a bowl liner which shall have a maximum resistance to distortion.

Another purpose is the provision of means for 10 preventing distortion or bending of the crusher bowl or frame surrounding the bowl liner.

Another purpose is the provision of improved means for mounting the bowl liner in a bowl.

Other purposes will appear from time to time 15 in the course of the specification and claims.

I illustrate my invention more or less diagrammatically in the accompanying drawing which is a vertical axial view taken on a plane including the general vertical axis of the crusher.

Like parts are indicated by like characters 20 throughout the specification and drawing.

Referring to the drawing, I generally indicate a crusher frame including a central fixed bearing sleeve 2 in which is rotatably mounted the sleeve 25 3, eccentrically apertured as at 4. It may be rotated for example through the gear 5 at the top of the sleeve which meshes with the pinion 6 on a drive shaft 7 which may be driven from any suitable source of power not herein shown. 8 is a supporting bearing member having an upper concave bearing surface 9 adapted to receive the corresponding downwardly convex spherical bearing surface 10 of a crusher head 11. 12 is a shaft to which the crusher head is secured, which shaft 30 extends downwardly into the eccentric aperture 4. 35 13 is any suitable mantle or wear taking part upon the head 10. The parts above described do not of themselves form part of the present invention but are described and shown as illustrating a structure to which my invention may be applied.

14 indicates a bowl structure suitably mounted upon the frame 1 and held in the position in which it is shown, for example, by the springs 15. The bowl structure includes an inverted bowl 45 member or wall 16 which is apertured as at 17 and provided with an upwardly and outwardly inclined bottom surface 18, the purpose of which will later appear.

19 generally indicates a bowl liner structure 50 having a generally conic rear face 20 and a forward or inner crushing face 21 of any suitable contour. It is thickened at the bottom as at 22, this thickened portion being provided with a surface 23 conforming to the opposed surface 18 of 55 the bowl structure 14. 24 indicates a securing

lug adapted to extend upwardly and inwardly through the aperture 17 to receive any suitable locking means, for example the U-bolt 25. It will be understood that any suitable number of lugs 24 and U-bolts 25 may be employed, whereby the entire bowl liner structure 19 is firmly upwardly drawn against the opposed inner surface 21 of the inverted bowl member 16.

26 indicates a layer of zinc or the like which is interposed between the inner face 20 of the liner 19 and the opposed conic face 21 of the bowl. It will be noted, however, that the surface 23 of the member 19 maintains a metal to metal contact with the opposed surface 18 of the bowl 16.

It will be realized that whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

Where I employ in the claims such terms as 25 "soft metal" "packing" or the like, it will be understood that I intend that term to be limited to the employment of highly ductile or soft metals, such as zinc, lead, Babbitt metal, or the like, which are commonly employed as packings in 30 gyratory crushers and which run or flow under pressure much more readily than do such metals as cast iron or the like.

The use and operation of my invention are as 35 follows:

In crushing practice, it is frequent to employ 40 wearing parts of manganese steel or other metals or alloys which are likely to expand or peen under heavy use. Manganese steel, for example, is exceedingly satisfactory in its wearing qualities but 45 it does become deformed under use. One purpose of my invention is to provide a bowl liner for a crusher in which the tendency of the part to deform or run is reduced to a minimum or is directed in such fashion as to prevent splitting 45 of the liner itself or the subjection of the bowl to undue and deforming stresses.

I find it desirable, for example, to employ the 50 upwardly and outwardly extending portion 23 as a species of lateral lock to distribute the thrust 50 and to prevent lateral displacement of the liner. When the liner is in the position shown in the drawing, with the U-bolts 25 drawing the lugs 24 upwardly, the entire liner is upwardly firmly held. The conic face 20 of the liner abuts against 55

a layer of zinc, but the metal to metal contact between the opposed surfaces 23 and 18 causes a direct thrust against the lower portion of the bowl 16.

5 Owing to the upward and outward inclination of the surface 23 and the opposed surface 18 of the bowl, the thrust is not only upward but inward, thus tending to balance the upward and outward thrust directed by the face 20 of the liner 19. Thus any tendency of the bowl member 16 to be outwardly deformed or bent is checked, the forces tending to balance. In this sense, the tight direct joint at 23 at the bottom of the bowl supports the casting in which the 10 bowl is formed, and prevents an outward bowing of the casting.

15 A further advantage is the provision of a tight connection between the opposed parts which, after the zinc has been poured into the space 20 between the bowl and liner, holds the part tight until the zinc and the opposed metallic faces assume a permanent seat. This initial period may extend for a week or more. The only metal to metal contact, in the sense of a thrust of opposed 25 hard metal surfaces against each other, is along the face 23, since the zinc acts in a sense as a cushion for the bond.

20 The toe-in connection at 23 prevents the bowl liner at the opposite side from drawing away 30 from the bowl in response to the crushing action at the closed side of the device.

25 As the metal in the liner flows under severe service, it has a tendency to become loose. The extension 22 at the lower end of the liner resists 35 movement of the bowl liner as a whole from the position which it assumes as it is pulled upward against the surface 18 of the crusher bowl. The position assumed by the cone in the drawing is that in which crushing occurs at the left of the 40 crushing cavity. The cone liner, therefore, is thrust toward the left and would normally be resisted by the zinc backing of the liner only. However, by virtue of the fact that the liner will 45 tend to move toward the left, it will clamp itself tightly on the edge 23 on the right of the liner, thereby resisting movement. This prevents cracking of the zinc and/or loosening of the liner.

I claim:

1. In combination in a gyratory crusher, a bowl having a generally conic upwardly and inwardly extending face and a generally conic upwardly and outwardly extending face, the two faces converging toward their lower edges, and a bowl liner of a metal having the general characteristics of manganese steel, said liner having a generally conic upwardly and inwardly extending face opposed to the corresponding face of the bowl and 5 a generally conic upwardly and outwardly extending face opposed to and in engagement with the corresponding face of the bowl, a layer of metal substantially more ductile than the metal of the liner extending between and substantially 10 throughout the opposed upwardly and inwardly extending faces of the two members and extending to the lower edges thereof, said opposed faces being normally entirely out of contact with each other, and securing means for holding the bowl 15 liner upwardly against the bowl, the angle of the upwardly and outwardly inclined conic faces from the horizontal being sufficient to prevent lateral movement in response to crushing stress.

2. For use in a gyratory crusher with a bowl 20 having a generally conic upwardly and inwardly extending face and a generally conic upwardly and outwardly extending face and a layer of highly ductile metal overlying the upwardly and 25 inwardly extending face from top to bottom 30 thereof, a bowl liner of a metal having the general characteristics of manganese steel, said liner having a generally upwardly and inwardly inclined crushing body having a generally conic 35 inner face and an outward flange at the lower 40 edge of said body extending circumferentially substantially entirely thereabout, said flange being formed with an upwardly and outwardly inclined generally conic top contact surface, all parts of which lie in horizontal planes intersecting the 45 inner conic face of the crushing body, the angle of said face from the horizontal being sufficient to prevent lateral movement of said liner in response to crushing stresses delivered against the upwardly and inwardly extending conic face 45 thereof.

OSCAR C. GRUENDER.
